DESULFURIZATION OF HYDROCARBONS BY EXTRACTION WITH PHENYLACETO- NITRILE

Norwood K. Talbert, Yorklyn, Del., assignor to
Phillips Petroleum Company, a corporation of
Delaware

Application June 8, 1951, Serial No. 230,527

16 Claims. (Cl. 260—608)

1

This invention relates to the separation of sulfur compounds and hydrocarbons from mixtures of them. In one of its aspects the invention relates to the removal of sulfur compounds from hydrocarbons. In another aspect the invention is concerned with the extraction of aliphatic disulfides from hydrocarbons. In still another of its aspects the invention relates to a process for the selective extraction of sulfur compounds from paraffinic and naphthenic hydrocarbons containing them, employing an agent novel for this purpose.

It is generally impossible to separate aliphatic sulfur compounds from hydrocarbon mixtures by fractional distillation because the sulfur compounds have boiling points within the boiling ranges of valuable hydrocarbons contained in the fraction, and, in some cases at least, azeotropes are formed.

Methods now employed for separating at least a portion of the sulfur compounds from hydrocarbons are solvent extraction and extractive distillation, using polar compounds which are preferential solvents for the sulfur compounds. Most of these solvents are unsatisfactory because they either have low aliphatic disulfide solubility or they are miscible with hydrocarbons; or, at best, they have limited selectivity for aliphatic disulfides.

A tabulation of a number of solvents and the reasons why each is not satisfactory for the removal of aliphatic disulfides from hydrocarbons is given in Table I. Ditetraaryloctyldisulfide was used as the representative of aliphatic disulfides, and normal heptane was used as the representative of paraffin hydrocarbons. In addition to the tabulation given in Table I, I have obtained data which shows the system benzonitrile-ditetraaryloctyldisulfide was completely miscible above approximately 38° F. for concentrations of disulfide from 31.5 weight per cent to 69.7 weight per cent.

2
TABLE I

Solvents tested for disulfide-paraffin separation

	Solvent	Remarks
5	n-Acetyl ethanolamine o-Anisidine	Immiscible with disulfide. Low selectivity for disulfide with respect to paraffins.
	n-Butyronitrile	Completely miscible with both paraffins and aromatics.
10	n-Capronitrile	Completely miscible with both paraffins and disulfides. Do.
	Di-n-propylamine 2-ethanolpyridine	Immiscible with disulfide. Do.
	4-ethanopyridine	Do.
	Ethyl cyanoacetate	Do.
	Ethylene cyanohydrin	Do.
	Ethylene glycol	Do.
15	Heptacosafuorotri-n-butyl amine.	Do.
	B-hydroxyethyl acetate	Do.
	B-hydroxyethylaniline	Do.
	Levulinic acid	Do.
	Methyl acetooacetate	Do.
	Methyl levulinate	Do.
20	Monoethanolamine	Do.
	o-Nitroanisole	Low selectivity for disulfide with respect to paraffins.
	Propylene glycol	Immiscible with disulfide.

It appears to be clear, in view of the table, that
25 a solvent agent which will be suitable to the sep-
aration of sulfur compounds, e. g., aliphatic di-
sulfides, is needed and difficult to find.

I have now found an agent with which aliphatic sulfur compounds may be separated from hydrocarbons, such as paraffins, and naphthenes. The agent is employed in a liquid-liquid extraction process or in an extractive distillation process and is phenylacetonitrile. Phenylacetonitrile has a great selectivity for aliphatic disulfides in the presence of hydrocarbons.

35 the presence of liquid-
A schematic flow diagram of a typical liquid-
liquid extraction process using phenylacetonitrile is given in Figure 1. In this process a di-
sulfide-paraffin mixture is processed to produce
40 a paraffin hydrocarbon product which is essen-
tially free from disulfides. The mixture is con-
tacted with the primary solvent, phenylacetonitrile, in unit I. The raffinate, paraffin hydro-
carbons saturated with phenylacetonitrile, is
45 processed in unit II to recover the primary sol-

vent. The extract from unit I, which is phenylacetonitrile containing dissolved disulfide concentrate, is contacted with a secondary solvent, which may be a light alkylate, in unit III. The secondary solvent and disulfide concentrate from unit III are separated in unit IV. Some of the disulfide concentrate from unit IV is returned to unit I as enriching liquid, and the remainder is sent to product storage. The secondary solvent from unit IV along with some make-up solvent is returned to unit III. The primary solvent from unit III which is saturated with secondary solvent is processed in unit V. The pri-

The liquid-liquid miscibility diagram for the phenylacetonitrile - ditertiaryoctyldisulfide - cyclohexane system at 77° F. has also been determined. Tie lines for this system were estimated on the basis of the tie lines for the above mentioned ternary system with normal heptane. The estimated compositions of the coexisting equilibrium phases are given in Table III. The estimated relative K for ditertiaryoctyldisulfide, relative to cyclohexane, varies between 3 and 6 and indicates that phenylacetonitrile is selective for aliphatic disulfides in the presence of naphthenes.

mary solvent recovered in unit V along with some make-up solvent is returned to unit I, and the recovered secondary solvent is returned to unit III.

The liquid-liquid equilibrium relationships for the phenylacetonitrile - ditertiaryoctyldisulfide-normal heptane system at 77° F. have been determined, and the compositions of the coexisting equilibrium phases are presented in Table II. Values of relative K are included in this table. The "relative K" is indicative of the selectivity of a solvent for a given compound in the presence of one or more other compounds. A compound can be removed from a mixture by a solvent when its relative K is greater than unity. Referring to Table II, it is seen that the relative K for ditertiaryoctyldisulfide relative to normal heptane varies between 3 and 26.

The temperature of the extractions of the invention depends on the disulfide being extracted, but ordinarily a range of temperatures of 50 to 100° F. are used when satisfactory.

This process is particularly directed to removing aliphatic disulfides from hydrocarbon oils such as gasoline, kerosene, naphthas, etc., which may be straight run distillates and which may be derived from petroleum crudes. Aliphatic disulfides are difficult or generally impossible to remove from these hydrocarbon mixtures by fractional distillation owing to azeotrope formation and to the fact that certain sulfur compounds have boiling points within the boiling ranges of valuable hydrocarbons contained in the fraction.

Detailed information concerning the phenylacetonitrile process for the removal of ditertiary-

octyldisulfide from normal heptane is given in Figure 2. The contactor, unit I, is provided with trays, risers and down-comers in order to obtain intimate contacting of the hydrocarbon phase with phenylacetonitrile. Any other suitable means of contacting the hydrocarbon phase with the solvent could have been used. The basis of the schematic flow diagram (Figure 2) is 1000 pounds of hydrocarbon feed. The feed is a binary mixture of normal heptane and diteriaryoctyldisulfide containing 1.0 weight per cent disulfide. The disulfide concentration of the normal heptane is reduced to 0.1 per cent by extraction with phenylacetonitrile. As the disulfide concentrate contains 65 weight per cent disulfide, the normal heptane loss in this stream is only 5 pounds per 1000 pounds of feed. The liquid-liquid contactor has three theoretical stages in the enriching section and two theoretical stages in the stripping section. The operating temperature of the contactor is 77° F. The quantities of phenylacetonitrile and enriching liquid (reflux) required per thousand pounds of feed are 573 and 297 pounds, respectively.

The raffinate from the contactor, unit I, is directed to unit II, which is a stripping column, wherein the normal heptane and phenylacetonitrile are separated. The phenylacetonitrile is returned to unit I, and the normal heptane, which is essentially free of disulfide, is directed to product storage. The extract from the contactor is processed in the hydrocarbon-solvent separation step wherein the operations illustrated by units III, IV and V of Figure 1 are accomplished. The phenylacetonitrile extract from unit I is contacted in unit III with the secondary solvent, which may be a light alkylate with a boiling range of 100° to 300° F. and preferably a narrower boiling range such as 210° to 240° F., or a hexane fraction with a boiling range such as 122° to 156° F. The disulfide concentrate is extracted from the phenylacetonitrile by the light alkylate. The disulfide concentrate and light alkylate are separated in a stripper, unit IV; 297 pounds of disulfide concentrate per thousand pounds of feed are returned to the contactor as enriching liquid, and the remainder, 14 pounds, is sent to product storage; the light alkylate is returned to unit III. The phenylacetonitrile from unit III which is saturated with light alkylate is processed in unit V. In unit V the light alkylate is stripped out of the phenylacetonitrile. The phenylacetonitrile is returned to unit I and the light alkylate is returned to unit III.

Reasonable variation and modification are possible within the scope of the foregoing disclosure, drawings, and appended claims to the invention; the essence of which is that phenylacetonitrile has been found to be an excellent selective solvent agent for the extraction or removal of sulfur compounds from hydrocarbons and that a method for such removal has been set forth as described.

I claim:

1. The removal of a sulfur compound from a hydrocarbon containing it which comprises the step of contacting said hydrocarbon with phenylacetonitrile.
2. The process of claim 1 wherein a liquid to liquid extraction method is employed.
3. The process of claim 1 wherein an extractive distillation method is employed.
4. The process of claim 1 wherein the tem-

perature is maintained in the range 50° F. to 100° F.

5. The removal of an aliphatic disulfide from a hydrocarbon by contacting said hydrocarbon with phenylacetonitrile, separating a raffinate containing hydrocarbon and phenylacetonitrile from a phenylacetonitrile-disulfide-containing extract and then recovering said disulfide from said extract.

10 6. The removal of a diteriaryoctyldisulfide from a hydrocarbon by contacting said hydrocarbon with phenylacetonitrile, separating a raffinate containing hydrocarbon and phenylacetonitrile from a phenylacetonitrile-disulfide-containing extract and then recovering said disulfide from said extract.

20 7. The removal of a diteriaryoctyldisulfide from n-heptane by contacting said n-heptane with phenylacetonitrile, separating a raffinate containing n-heptane and phenylacetonitrile from a phenylacetonitrile-disulfide-containing extract and then recovering said disulfide from said extract.

25 8. The process for the separation of an aliphatic disulfide from a substantially saturated hydrocarbon containing it which comprises contacting said hydrocarbon with a primary solvent essentially phenylacetonitrile, separating from the contacted admixture, thus obtained, a raffinate containing hydrocarbon and phenylacetonitrile, separating phenylacetonitrile from the raffinate, separating a hydrocarbon fraction, essentially free from disulfide, as a product of the process, returning the phenylacetonitrile to the contacting step of the process, separating from the said contacted admixture an extract rich in disulfide, treating said extract with a secondary solvent to extract disulfide therefrom, separating disulfide from said secondary solvent as another product of the process, recovering phenylacetonitrile from said solvent and reusing both the last recovered phenylacetonitrile and secondary solvent in the process as before.

45 9. The process for the separation of diteriaryoctyldisulfide from a heptane containing it which comprises contacting said heptane with a primary solvent essentially phenylacetonitrile, separating from the contacted admixture, thus obtained, a raffinate containing heptane and phenylacetonitrile, separating phenylacetonitrile from the raffinate, separating a heptane fraction, essentially free from disulfide, as a product of the process, returning the phenylacetonitrile to the contacting step of the process, separating from the said contacted admixture an extract rich in disulfide, treating said extract with a secondary solvent to extract disulfide therefrom, separating disulfide from said secondary solvent as another product of the process, recovering phenylacetonitrile from said solvent and reusing both the last recovered phenylacetonitrile and secondary solvent in the process as before.

60 10. The recovery of diteriaryoctyldisulfide from normal heptane which comprises contacting the normal heptane containing said disulfide with phenylacetonitrile in the liquid phase, separating said contacted admixture into raffinate and extract phases, said raffinate phase containing normal heptane and phenylacetonitrile, separating normal heptane from phenylacetonitrile as a product of the process and returning said separated phenylacetonitrile to the contacting step, contacting the said extract phase containing phenylacetonitrile and disulfide with a light hydrocarbon alkylate boiling in the range of 100°

to 300° F. thus separating a disulfide concentrate from the phenylacetonitrile, then separating the disulfide concentrate from the light alkylate and removing disulfide as a product of the process while returning some disulfide as enriching liquid to the contacting step, returning the alkylate to the step in which the extract phase is contacted with light alkylate, and returning the phenylacetonitrile to the first mentioned contacting step.

11. The process of claim 10 wherein the light alkylate has a boiling range of from 210° to 240° F.

12. The process of claim 10 wherein the light alkylate is essentially a hexane fraction boiling within the approximate range 122° to 156° F.

13. The process of claim 10 wherein the temperature during the contact of the phenylacetonitrile and the heptane is maintained at approximately 77° F.

14. The removal of sulfur compounds from a 20 saturated hydrocarbon with phenylacetonitrile which comprises contacting said saturated hydrocarbon with phenylacetonitrile to obtain an

extract phase and a raffinate phase, separating a raffinate containing said hydrocarbon and phenylacetonitrile from a phenylacetonitrile-sulfur compound containing extract and then recovering said sulfur compound from said extract.

15. A process according to claim 14 wherein said saturated hydrocarbon is an aliphatic hydrocarbon.

16. The process of removing a sulfur compound from a hydrocarbon containing the same which comprises extracting said sulfur compound from said hydrocarbon employing phenylacetonitrile as an extractant.
